UNITED STATES PATENT OFFICE.

FRANCIS I. FREEMAN, OF PITTSBURG, PENNSYLVANIA, ASSIGNOR TO THE TOTTEN & HOGG IRON AND STEEL FOUNDRY COMPANY, OF SAME PLACE.

SWITCH DEVICE FOR FEED-TABLES.

SPECIFICATION forming part of Letters Patent No. 618,858, dated February 7, 1899.

Application filed January 25, 1898. Serial No. 667,904. (No model.)

To all whom it may concern:

Be it known that I, FRANCIS I. FREEMAN, of Pittsburgh, in the county of Allegheny and State of Pennsylvania, have invented a new and useful Improvement in Switch Devices for Feed-Tables, of which the following is a full, clear, and exact description, reference being had to the accompanying drawings, forming part of this specification, in which—

5. • o Figure 1 is a partial longitudinal section of a feed-table provided with my improved switch mechanism, and Fig. 2 is a top plan view of the same.

15. My invention relates to the devices employed for removing sheets or articles from a feed-table over which they are being carried and is designed to improve the construction of such devices and make their operation more easy and certain.

20. • o In the drawings, 2 represents a feed-table having a longitudinal series of lower rollers 3, which may be driven by sprocket-chain connections, as indicated in Fig. 2, or otherwise, as desired. Between these lower rollers are located the supporting plates or aprons 4, and with the lower rollers are used a series 25. of upper idle-rollers 5, which rest loosely thereon and are merely driven by friction from the lower rollers or from the sheet passing between the rollers. Between two sets of the upper and lower rollers at any desired 30. point along the length of the table I cut away one of the aprons 4 and replace the cut-away portion with a swinging apron 6, which is 35. operated by a projecting lever-handle 7. When this apron 6 is thrown into its inclined position, as shown in Fig. 1, it registers with the end of a stationary inclined apron 8, which leads to a pair of small rollers 9, the upper of 40. which is positively driven by gearing 10, connecting it with one of the rollers 3. Beyond the rollers 9 the apron is continued, so as to form an elongated support 11, upon which the sheets are driven. The feed-roller 5, adjacent 45. to the rollers 9, is reduced in diameter, so as to allow the positioning of the apron thereover, and this roller, as well as the upper one of the rollers 9, is preferably spring-pressed, as shown, so as to give them a sufficient grip 50. upon the sheet and which might not otherwise be obtained on account of their reduced

size and weight. At the lower end of the inclined apron 8 I preferably bend it, as shown at 12, so as to provide a guide-shield.

The operation is apparent. The swinging 55 apron 6 normally lies horizontally in a line with the aprons 4 between the rollers and in this position acts merely as a support over which the sheets pass. When it is desired to remove a sheet from the table, the plate 60 6 is swung into its inclined position, and being either secured or held by the operator in this position the sheet will be guided upwardly along this plate and the apron 8 and into engagement with the rollers 9, which 65 will force it onto the support 11. The swinging apron 6 may be swung back into normal position as soon as the front end of the sheet has passed upon the apron 8, and the removal of this sheet will in no wise interfere 70 with the succeeding sheets or articles.

The advantages of my invention result from the use of the swinging plate, which normally lies in a substantially horizontal plane between the feed-rollers, but which 75 when tilted guides the sheets or articles upwardly upon the apron.

Many changes in the form of this swinging plate or apron, as well as in the arrangement of the feed-table, may be made without departing from my invention, since 80

What I claim is—

1. The combination with a feed-table having a longitudinal series of feed-rollers over and in contact with the upper surfaces of 85 which the metal passes, of a pivoted plate which normally rests entirely below the path of the metal passing over the rollers, and between certain of the rollers, and means for tilting the plate into inclined position across 90 the path of the metal to deflect it from the table, substantially as described.

2. A feed-table having a longitudinal series of positively-driven feed-rollers, a series of idle-rollers coacting therewith, a pivoted 95 plate lying normally in horizontal position between certain of the rollers and below the tops of the lower series of rollers, the free end of the plate extending in the direction of the feed, and means for tilting the plate into 100 an inclined position across the line of the feed, substantially as described.

3. A feed-table having a longitudinal series of positively-driven feed-rollers, a pair of driven feed-rollers located above the same, and a swinging apron lying normally in a horizontal plane between the lower rollers and arranged when tilted to direct the article to the upper feed-rollers, substantially as described.

4. A feed-table having a longitudinal series of positively-driven feed-rollers, a series of idle-rollers coacting therewith, a pivoted plate lying normally in a horizontal plane be-

tween the rollers, and upper driven rollers arranged to seize the sheet and remove it from the table, the plate being arranged when tilted to guide the sheet into these upper rollers, substantially as described. 15

In testimony whereof I have hereunto set my hand.

FRANCIS I. FREEMAN.
